(21) Appl. No.: **29/257,025**

The ornamental design for a “bluetooth earphone and adapter,” as shown and described.

(22) Filed: **Mar. 29, 2006**

DESCRIPTION

(51) LOC (8) Cl. **14-01**

FIG. 1 is a perspective view of a “bluetooth earphone and

(52) U.S. Cl. **D14/223**

adaptor” showing my new design;

(58) Field of Classification Search D14/137,

FIG. 2 is a front view thereof;

D14/138, 142, 147, 148, 150, 155, 191, 240,

FIG. 3 is a rear view thereof;

D14/299, 181, 188, 192, 205, 206, 223; 320/111,

FIG. 4 is a left side view thereof;

320/113; 379/430, 431, 454, 455; 381/374,

FIG. 5 is a right side view thereof;

381/380, 381; 455/573

FIG. 6 is a top view thereof;

See application file for complete search history.

FIG. 7 is a bottom view thereof;

(56) **References Cited**

FIG. 8 is a perspective view of the support in an opened state; and,

U.S. PATENT DOCUMENTS

FIG. 9 is an exploded view thereof.
